UNITED STATES PATENT OFFICE

2,440,470

CHAIR

Meyer Greitzer, Los Angeles, Calif.

Application March 21, 1945, Serial No. 583,906

7 Claims. (Cl. 155—194)

1

My invention relates to chairs, particularly of the type covered by U. S. Letters Patent #2,306,878 issued to me December 29, 1942, and Patent #2,390,878 issued to me December 11, 1945.

The principal object of my present invention is, to generally improve upon and simplify the construction of the chairs covered by my aforesaid patent and copending patent application, particularly the frames of the chair seat and the chair back and the means utilized for mounting the chair back on the chair frame.

Further objects of my invention are, to provide simple, practical and convenient means for mounting the seat upon the chair frame; to provide improved means for mounting the panels and upholstered parts of the chair back and seat upon their frames, and further, to provide a chair of the character referred to, which has no nail, tack or screw heads exposed so as to scratch and mar the surfaces of walls, chairs and other articles of furniture with which they might contact.

Further objects of my invention are, to provide a chair which may be readily assembled or taken apart, also to provide a chair which combines simplicity of construction with strength, rigidity and minimum weight and at the same time, presenting a neat finished and pleasing appearance.

Further objects of my invention are, to provide a chair of the character referred to which requires only a few screws or like fastening devices, few tools for assembly and disassembly and to provide a chair which may be readily knocked down so as to occupy little space when stored or packed for transportation, thus affecting a substantial saving of storage and shipping charges.

With the foregoing and other objects in view, my invention consists in certain novel features of construction and arrangement of parts which will be hereinafter more fully described and claimed and illustrated in the accompanying drawings, in which:

Fig. 1 is a perspective view of my improved chair.

Fig. 2 is an elevational view partly in section, of the chair back.

Fig. 3 is a detail sectional view of a modified form of a joint in the chair back frame.

Fig. 4 is a cross section of the modified frame shown on Fig. 3, as taken on the line 4—4 thereof.

Fig. 5 is an enlarged detail section taken on the line 5—5 of Fig. 2.

Fig. 6 is an enlarged cross section taken on the line 6—6 of Fig. 2.

Fig. 7 is a cross section similar to Fig. 6 and showing a modification.

Fig. 8 is a cross section similar to Fig. 6 and showing a further modified construction.

Fig. 9 is a plan view of the chair seat with parts broken away and in section.

2

Fig. 10 is an enlarged vertical section taken on the line 10—10 of Fig. 9.

Fig. 11 is an enlarged detail section taken on the line 11—11 of Fig. 9.

Fig. 12 is an enlarged detail section taken on a vertical plane, of the connection between the chair back and chair frame.

Referring by numerals to the accompanying drawings which illustrate a preferred embodiment of my invention, 10 designates generally, the chair frame which is formed from a single piece of metal tubing bent to form a horizontally disposed U-shaped base 11, a pair of vertically disposed front legs 12, horizontally disposed seat supporting rails 13 and upright back supporting members 14.

The seat back comprises a rectangular frame preferably formed from a single piece of extruded cast, or molded metal or plastic materials, and comprising a strap-like body portion 15 having on its inner face, a pair of spaced parallel flanges 16 and its outer face being ribbed or corrugated longitudinally, so as to produce a more or less pleasing and finished effect.

Where formed from extruded metal, the ends of the member 15 may be brought together and welded as designated by X, Fig. 2 or said ends may be united by means of a joint member 17 and screws or rivets 18, as illustrated in Figs. 3 and 4.

The lower corners of the seat back frame are mounted on the upper ends of frame members 14 by means of pins 19, which depend from the lower ends of blocks 20, of wood, plastics or the like, that are positioned between widened portions of the flanges 16, at the lower ends of the upright side members of said frame and said blocks being secured to said flanges by nails or screws 21 (see Figs. 5 and 12).

Pins 19 pass through apertures 22 in the lower corners of the seat back frame and enter the upper portions of members 14 of the tubular frame 10 and when so positioned, the portions 11, 12 and seat supporting members 13 of the frame, are positively maintained in spaced relation and securely held against any lateral expansion or contraction.

A seat back rear panel 23 of sheet metal, wood or plastics is positioned in the rear portion of the seat back frame against the rear one of the flanges 16 and a front panel 24 which may be suitably upholstered, is positioned in the front portion of said frame against the front one of the flanges 16.

The panels may be secured to each other and to the frame, by means of screws 25 having their heads countersunk in back panel 23 as seen in Fig. 6, or such fastening means may take the form of pins 26 passing through the panels with 60 one pin carrying on its inner end, a socket 27,

for the reception of a stud on the end of the other pin, which arrangement functions after the manner of a conventional snap fastener (see Fig. 7).

Where the chair back frame is formed from a strip of extruded metal or plastics bent to shape and its ends welded together, the strip may be formed with spaced grooves such as 28 (see Fig. 8) for the reception of the edges of the panels 24 and 24; such construction eliminating the fastening means such as the screws 26 and snap fasteners 26, 27.

The chair seat, seen in Figs. 9 to 12 inclusive, comprises a substantially rectangular frame 29, preferably formed in a single piece from extruded, cast, die cast or molded metal or plastics provided a short distance below its upper edge with an inwardly presented flange 30 and its outer face being ribbed or corrugated lengthwise to provide a pleasing, finished effect.

Where this frame is formed from a piece of extruded metal, the ends may be brought together on the rear side of said frame and united by welding, or by means of a joint member 31 and screws or rivets such as 32 (Fig. 11).

Formed integral with or secured to the side rails of the seat frame 29 by welding or otherwise, below flanges 30 are inwardly and downwardly projecting projecting brackets 33 having curved under faces providing seats for the rails 13 of the seat frame and projecting outwardly from the lower ends of these brackets are short studs 34 which, when the seat is applied to the frame, enter apertures 35 in rails thus firmly securing the seat on said frame.

To position the seat on the frame, rails 13 are spaced apart a sufficient distance to enable studs to enter apertures 35 as said rails flex back to their normal positions and when the seat back is applied to the upper ends of members 19, the upper portion of the chair frame is securely held against lateral expansion or contraction so that the seat is firmly anchored on rails 13 of said frame.

A seat panel 36, preferably upholstered, is positioned in the seat frame 29, with its edges resting on flange 30 and the upper edge of said frame may be turned or extended slightly inward, as seen in Fig. 10, so as to overlie the edge of said panel and thereby retain same in the frame.

Where the seat frame and seat back frame are formed of metal, their exposed surfaces may be plated or polished so as to present an attractive and pleasing appearance.

If desired, a spring cushioned seat may be positioned in the seat frame.

Thus it will be seen that I have provided a chair which is simple in structure, inexpensive of manufacture, capable of being readily fabricated and which is very effective in performing the functions for which it is intended.

It will be understood that minor changes in the size, form and construction of the various parts of my improved chair may be made and substituted for those herein shown and described without departing from the spirit of the invention, the scope of which is set forth in the appended claims.

I claim as my invention:

1. In a chair, the combination with a frame, including a base, front legs, seat supporting rails and tubular back supporting members projecting upwardly from the rear ends of said rails and

a seat supported by said rails, of a chair back comprising a frame having upright end pieces which are channel shape in horizontal section, rectangular blocks disposed between and secured

5 to the flanges on the lower portions of said end pieces, pins depending from said blocks, which pins pass through the ends of the lower rail of the chair back frame, and are seated in the upper ends of said back supporting members, and

10 a front panel removably seated in said chair back frame.

2. In a chair, the combination as set forth in claim 1, with a rear panel seated in said chair back frame and fastening means securing said front and rear panels.

3. In a chair, the combination with a frame including a base, front legs, seat supporting rails provided on their inner side portions with apertures and tubular members projecting upwardly from the rear ends of said rails and a chair back

20 carried by said upwardly projecting members, of a seat frame having side rails, brackets secured to the side rails of said seat frame, lugs projecting from said brackets, which lugs are engaged

25 in the apertures in the seat supporting rails of said frame and the underfaces of which brackets and upper inner faces of said seat supporting rails are correspondingly contoured so as to provide a snug fit and bearing between said brackets

30 and rails.

4. In a chair, the combination as set forth in claim 3 with a seat panel positioned in said seat frame.

5. In a chair, the combination as set forth in claim 3 with a flange projecting inwardly from the members forming said seat frame above said brackets and a seat panel positioned within said frame and resting upon said flange.

6. In a chair, a frame, having seat supporting rails in the inner portions of the walls of which are formed horizontally disposed apertures, a seat frame, brackets secured to said seat frame and provided with seats for the rails of the chair frame and lugs projecting outwardly from the lower ends of said brackets for engagement in the apertures in the rails of said chair frame.

7. The chair as set forth in claim 6 and a seat panel positioned in said seat frame.

MEYER GREITZER.
